CLAIM

The ornamental design for a support for lower cover of reticle box, as shown and described.

DESCRIPTION

FIG. 1 is a perspective view of a support for lower cover of reticle box showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is another perspective view thereof;

FIG. 9 is a perspective view showing the support for lower cover of reticle box of FIG. 1 in each corner of the environmental structure of a lower cover of reticle box; and, FIG. 10 is a partial enlarged view of encircled portion 10 of FIG. 9.

The evenly-dashed broken lines shown in FIGS. 9 and 10 represent environmental structure and form no part of the claimed design. The dot-dash broken lines shown in FIGS.

(Continued)

9 and **10**, encircle portions of the support for lower cover of reticle box that are illustrated in enlargements, and form no part of the claimed design.
